[57] CLAIM

The ornamental design for a bicycle carrier for automobiles, substantially as shown and described.

DESCRIPTION

FIG. 1 is a perspective view of a bicycle carrier for automobiles showing our new design.

FIG. 2 is an elevational view on an enlarged scale of one of the two allochiral sides thereof.

FIG. 3 is an end elevational view thereof as seen from the right side of FIG. 2.

FIG. 4 is an end elevational view thereof as seen from the left side of FIG. 2.

FIG. 5 is a top plan view thereof as seen in FIG. 2.

FIG. 6 is a side elevational view similar to FIG. 2 but showing the carrier arms in an alternate position.

FIG. 7 is an end elevational view thereof as seen from the right side of FIG. 6.

The broken lines in FIG. 1 of the drawings are for illustrative purposes only.
